The American Foundry Equipment Company,
Mishawaka, Ind., a corporation of Delaware

Application October 7, 1938, Serial No. 233,741

21 Claims.

(Cl. 51—9)

This invention relates to an improved centrifugal abrasive projecting machine designed to throw abrasive in a directed stream at velocities effective to clean the surfaces of castings, forgings, bars, sheets and like metallic objects so as to remove encrusted sand and scale from the surface thereof.

Centrifugal abrasive projecting machines now in use comprise a rotor head mounted for rotation at high speeds having a plurality of abrasive projecting blades mounted thereon which extend inwardly short of the axis of rotation of the rotor head to provide a central abrasive receiving space. A normally stationary tubular control member extends into the said central space and is provided with a discharge outlet in the tubular sidewall thereof. An impeller comprising a plurality of spaced abrasive propelling vanes is positioned within said control member and is fixed to rotate with said rotor head. Abrasive supplied to said propeller by a feed pipe is thrown by the impeller vanes outwardly through the discharge outlet in the tubular control member, where it is picked up by the inner ends of the rotating blades and thrown against the work piece to be cleaned or treated.

It will be appreciated that in a structure of the type above described, operating clearances must be provided between the rapidly rotating impeller vanes and the normally stationary tubular control member within which the propeller vanes are positioned. Abrasives normally used for blast cleaning and treating of metal objects comprise such material as hard quartz sand, steel grits or shot, which materials are free-flowing. Such abrasive materials having a relatively high specific gravity, are violently affected by centrifugal forces acting upon them, and due to their flow characteristics are to a certain extent affected by air currents promulgated by the fan action of the rapidly rotating impeller vanes and projecting blades.

A small but nevertheless highly objectionable percentage of the abrasive material fed into the impeller and tubular control member of present centrifugal abrasive projecting machines will not be discharged by the impeller vanes through the discharge outlet in the tubular control member, but will flow or move rearwardly through the clearance space provided between the impeller vanes and the tubular control member, which uncontrolled abrasive is commonly designated as stray abrasive. This stray abrasive continues its irregular movement through this clearance space, rebounding between the rotating neck portion

of the impeller at the rear of the impeller vanes and the stationary tubular control member, where it exerts a grinding wear upon the adjacent stationary and moving parts of the machine.

It has heretofore been attempted to reduce the quantity of stray abrasive moving rearwardly of the rotor by the provision of a circular rim or flange extending inwardly from the inner end of the tubular control member, which flange seats behind the impeller vanes. It will be appreciated that, operating clearances must also be provided between the inner edge of this flange and the neck portion of the rotating impeller. It is therefore impossible to completely seal this clearance space between the rotating impeller and the stationary tubular control member with any mechanical element so as to prevent the rearward movement of this stray abrasive.

The stray abrasive lodging between the normally stationary tubular control member and the rotating parts of the propeller eventually escapes by passing around the inturned flange of the tubular control member, where centrifugal force acts upon the freed stray abrasive to cause it to fly outward. This outward flying abrasive, free of the tubular control member, is picked up by the abrasive propelling blades and is thrown helter-skelter in all directions. This uncontrolled stray abrasive has a severe abrading action, due to the velocity imparted to it by the rotating blades, with the result that it wears the protective casings and other mechanisms surrounding the rotor, without coming into cleaning contact with the work piece positioned at one side of the rotor. It will also be appreciated that this stray abrasive is broken up and damaged without doing any useful work, but actually doing destructive work. This stray abrasive, free of the tubular control member, is often thrown against the rotor head during its outward movement, with the result that the adjacent rotor head and other parts of the machine are also abraded thereby.

It will also be appreciated that the flange portion extending inwardly from the inner end of the tubular control member must also be accurately centered with respect to the neck portion of the rotating propeller and must also be properly spaced between the adjacent impeller vanes and the rear wall surface of the rotor head to provide proper operating clearances between these points. When the impeller is in position, it is difficult, if not impossible, to visually determine whether proper axial and lateral clearances are provided between the normally stationary inturned flange

of such a tubular control member and the rotating parts of the mechanism. When the tubular control member is improperly positioned, there is further severe grinding between the stationary and moving parts. It will also be appreciated that such tubular control member cannot be removed from the machine without first removing the impeller so that considerable time is required in adjusting, removing and replacing 10 worn operating parts.

It is an object of this invention to improve upon centrifugal projecting abrasive machines now in use so as to obtain improved directional firing qualities and operating efficiencies and to 15 relieve operating parts of the machine from damaging wear caused by stray abrasive.

Another object of this invention is to provide an improved centrifugal abrasive projecting machine having means to relieve the machine of 20 such stray abrasive and abrasive fines which cannot be controlled in such a manner that this material will be discharged substantially without abrading or wearing velocity.

Another object of this invention is to provide 25 an improved abrasive control device which is provided with means for conducting rearwardly moving stray abrasive and abrasive fines back to a position where it may be discharged from the abrasive discharge outlet provided in said abrasive control device.

Another object of this invention is to provide an improved abrasive impeller designed to be positioned within the tubular control member of a bladed abrasive throwing rotor which impeller is provided with means to create an air current moving in such a direction as to substantially prevent any rearward movement of stray abrasive and abrasive fines through the clearance between the rotating propeller and the normally stationary tubular control member.

Another object of this invention is to provide an improved directional control device and impeller device having co-operating means which greatly limit or prevent rearward movement of stray abrasive and which perform the further function of returning such stray abrasive to a point where it can be engaged by the rotating impeller and thrown through the abrasive outlet provided in the control device.

A further object of this invention is to provide an improved centrifugal abrasive projecting machine having means for balancing air pressures within said machine during rotation thereof and remove objectionable movements of the abrasive in said machine caused by undesirable air currents and air disturbances.

Various other features and advantages of the invention will be apparent from the following description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a side elevational view of the improved abrasive throwing wheel showing the supporting brackets for adjustably mounting the feed spout and tubular control member;

Fig. 2 is a vertical cross-sectional view of the abrasive throwing wheel, showing certain details

of the improved tubular control member and impeller with abrasive and air vent passages in the hub of the wheel, this view also showing in section the supporting brackets upon which the feed spout and tubular control member are adjustably supported, this view being taken on line 2-2 of Fig. 1;

Fig. 3 is a cross-sectional view of the abrasive throwing wheel and associated tubular control member and impeller, taken along a plane at right angles to the axis of rotation of the wheel and looking in the direction of the arrows 3-3 of Fig. 2;

Fig. 4 is a rear face view of the wheel showing particularly the vent passages in the hub as they appear when looking in the direction of the arrows 4-4 of Fig. 2;

Fig. 5 is an enlarged fragmentary cross-sectional view through the tubular control member and impeller, a fragmentary portion of the tubular control member being broken away to more clearly show the vent passages in the hub, this view being taken along lines 5-5 of Fig. 2;

Fig. 6 is a perspective view of the abrasive impeller, the impeller being positioned centrally of 25 the rotor when assembled thereto;

Fig. 7 is a side elevational view of the tubular control member, certain parts thereof being broken away to more clearly illustrate the interior construction thereof;

Fig. 8 is a transverse cross-sectional view of the hub as it appears when removed from the wheel, and when looking at a section thereof in the direction of the arrows 8-8 on Fig. 2;

Fig. 9 is a top plan view of the feed funnel, 35 feed pipe and supporting bracket as it appears when looking in the direction of the arrows 9-9 on Fig. 1;

Fig. 10 is a cross-sectional view taken at the juncture of the feed funnel and the feed spout 40 looking in the direction of the arrows 10-10 on Fig. 1;

Fig. 11 is a cross-sectional view of the feed spout and supporting bracket therefor, this view being taken on line 11-11 of Fig. 1;

Fig. 12 is a cross-sectional view through a portion of the tubular control member and its supporting bracket, this view being taken along line 12-12 of Fig. 1; and

Fig. 13 is a side elevational view of the feed spout and control cage supporting bracket.

Similar reference characters refer to similar parts throughout the drawings and specification.

Referring more particularly to Figs. 1 to 4 inclusive of the drawings, the improved centrifugal abrasive projecting machine comprises a rotor structure W supported by a hub h carried by a shaft 21 adapted to be rotated at high speed. The rotor W comprises more particularly a side wall plate 1 of generally circular form upon which is rotatively supported a plurality of generally radially extending abrasive propelling blades b which extend inwardly short of the axis of rotation to define a central space 8 which receives a tubular control member c. An impeller member i, which may be formed as a one piece casting, is positioned within the tubular control member c and is fixed to the hub h so as to rotate therewith. An abrasive supply conduit f is provided which is arranged in inclined position to feed the abrasive into the impeller member i.

The blades b may be conveniently mounted upon the rotor plate 1 by providing a second rotor plate 2 spaced from the rotor plate 1, which plates are connected at suitable intervals by studs 3 75

having reduced ends 4 which extend into openings bored in the rotor plates 1 and 2. It will be noted that the studs 3 are provided with shoulders 5 against which the plates 1 and 2 seat so as to hold them in fixed spaced relation, the studs 3 being permanently connected with the plates 1 and 2 by welding 6 at the reduced ends 4 of the studs 3.

It will be noted, by referring to Fig. 2, that both the rotor plates 1 and 2 are each provided with a central opening 7, whose peripheral edges are generally in axial alignment with the interior ends 12 of the blades b, thus providing a truly circular central space 8 within which the tubular control member c is received. By referring more particularly to Figs. 2 and 3 it will be noted that the rotor plates 1 and 2 are also provided with a plurality of radially extending grooves 9 which are arranged in pairs so as to receive the respective adjacent side edges of the blades b.

The blades b are preferably made of a metallic material which is resistant to abrasive wear and is sufficiently tough and strong to stand up under the shocks incident to operation. Each of the blades b comprise generally a bottom wall portion 10 which may be of increased thickness at the outer end 13 thereof and which tapers to an edge at the inner end 12 thereof as shown in Fig. 3. Side flanges 11 extend along each side edge of the blade which are preferably of uniform height throughout so as to rather snugly fit within the grooves 9 provided in the rotor plates 1 and 2. Each blade b may be held in fixed operative position by a threaded set screw 15 which extends through a threaded aperture in the rotor plate 2 and which is provided with a tapered inner end 16 which seats within a half conical groove 14 provided on the rear face of the blade b. The outside face of each set screw 15 when in operative position is substantially flush with the outside face of the rotor plate 2, and may be provided with a tool engaging slot 17 into which a screw driver or other tool may be inserted to manipulate the set screw. It will be appreciated that the blades b may be quickly and easily removed by partially withdrawing the set screw 15 so as to permit the blades b to slip out through the periphery of the rotor. The blades however are fixedly held in secure operative position when the set screw 15 is turned inward so that the conical end 16 seats within the half conical recesses 14 in the blade. All of the blades b of the rotor may be similar in construction and similarly mounted.

The hub h may be made from a single casting comprising a sleeve portion 20 and a heavy flange portion 20a which has a large central bore into which the end of the drive shaft 21 snugly fits. The drive shaft 21 may be fixedly held to the hub h by one or more splines 22. As thus assembled, it will be noted that the interior end of the shaft 21 is visible through the central space of the rotor prior to the insertion of the impeller i. The hub h is secured to the rotor w by means of a plurality of spaced threaded bolts 23 which extend through the hub flange 20a and into threaded apertures in the rotor plate 1. A ring covering 24 of rubber or other abrasive-resisting material may be attached to the peripheral edge of the flange portion 20a of the hub so as to protect the flange portion from the abrading action of rebounding abrasives.

The control member c is tubular in cross-section and has a substantially truly cylindrical ex-

terior surface. The control member is provided with an abrasive discharge outlet 32 of generally limited peripheral length. Assuming that the rotor shown in Fig. 3 is rotating clock-wise, the abrasive would be thrown out of the discharge opening 32 of the control member by the impeller i in a stream flowing somewhat to the right of the radial line. To facilitate ejection of the abrasive, a forward edge 34 of the discharge outlet 32 may be inclined as shown in Fig. 3, while the rear edge 33 of the outlet 32 may or may not be so inclined. If desired, the walls of the tubular control member may be slightly thickened at the point 34 which part normally receives the greatest wear. It will also be noted by referring to Fig. 2 that the side edges 35 of the discharge outlet 32 reside slightly within and between the inside faces of the flanges 11 of the blades. If desired, the inside faces of the flanges 11 of the blades adjacent their inner ends may be tapered inwardly as at 18 to assist in guiding the abrasive from the discharge outlet 32 on to the bottom wall portion 10 of the blade.

It will be noted by referring more particularly to Fig. 2 that when the tubular control member c is in operative position, the interior end 36 thereof extends into a circular recess 29 provided in the hub h, such clearance being provided to permit free rotation of the hub h while the tubular control member c remains stationary. Leading outwardly from the circular recesses 29 in the flange portion 20a of the hub h, is a plurality of vent passages 25. As will be more fully brought out hereafter, the circular recess 29 in which the interior end 36 of the tubular control member c extends is adapted to receive any stray abrasive that may work its way rearwardly of the rotor, this abrasive then being promptly ejected through the vent passages 25. It will be noted that the vent passages are relatively close to the shaft 21 and the axis of rotation of the rotor so that any stray abrasive that may be ejected from the vent passage 25 has no substantial abrading velocity and consequently does little or no damage to the surrounding mechanism.

While I have shown a vent passage 25 for each blade of the wheel, it will be appreciated that any number of vent passages may be provided. Each vent passage 25 is defined by a lower wall 26 and a top wall 27 and substantially parallel side walls 28. The top wall 27 and the bottom wall 26 flare apart outwardly so that the opening of the passage 25 is larger at the discharge end than at the end where it leads into the circular recesses 29. The circular recesses 29 may be cut out or depressed at points 31 adjacent each vent passage 25, as shown particularly in Figures 5 and 8, so as to further facilitate the outflow of stray abrasive through the vent passages.

The upper portion of the tubular control member c may be cut away at the point where it emerges beyond the rotor disk 2 so as to provide entrance room for the discharge end of the feed pipe f. The lower half portion of the tubular control member c may be provided with an outwardly extending arcuate foot or saddle portion 37 which provides means for rigidly securing the tubular control member to a suitable support.

The tubular control member c feed spout f and feed funnel 72 may be rigidly but adjustably supported upon a suitable support which will now be described. A fixed and rigidly mounted platform positioned in front of the rotor, supports the bracket structure. This platform may comprise a heavy angle iron having a generally horizon-

tal extending support flange 51 and a downwardly extending stiffening flange 50. A flat plate 51a may also be positioned upon the horizontal flange 51 to provide a smooth and level seat for a main supporting bracket 52, which bracket comprises an upwardly extending flange portion 53 and a horizontal extending foot portion 54 which sets upon the plate 51a, a stiffening web 55 joining the flange portion 53 to the foot portion 54. As shown more particularly in Figs. 1, 12 and 13, a pair of bolts 56 are provided which extend through elongated slots 56a in the foot portion 54 of the bracket and through circular openings in the plate 51a and flange 51. Thus the foot portion 54 of the bracket may be moved a certain amount to the right or left as shown in Fig. 1 for a purpose which will hereafter be brought out.

The tubular control member is supported upon an arcuate shaped saddle 60 which is connected to flange 53 of the main bracket 52 by a secondary bracket 57. The secondary bracket 57 is provided with a vertically extending leg portion 58 which seats against the flat face of the flange 53 on the main bracket, bracket 57 being held thereto by a pair of spaced bolts 59 as shown in Fig. 11 which extend through horizontally elongated slots 59a provided in the leg portion 58 and through vertically elongated apertures 59a in the flange portion 53 of the main bracket. The secondary bracket 57 is provided with a horizontally extending leg portion 61 which is also provided with horizontally elongated slots 62a through which bolts 62 extend, the bolts 62 extending through circular apertures in the handle portion 63 of the saddle 60.

Referring more particularly to Figs. 1, 2 and 12, it will be noted that the saddle 60 is provided with a generally arcuate surface 64 which extends under the saddle portion 31 of the tubular control member c and generally conforms to the circular contour thereof. A clamping bar 65 has an arcuate foot portion 66 which rests upon the saddle 60 and an arcuate belly portion 66a which extends into the saddle portion 31 of the tubular control member c and conforms generally to the contour thereof. A clamp bolt 67 extends through a circular aperture 70 in the clamping bar 65 and the head 68 of the bolt is of such size as to be insertable through an enlarged opening 69 in the saddle 60. When the clamping bar 65 with the associated bolt 67 is pushed forwardly toward the rotor disc 1 the bolt head 68 slides into a bayonet slot 69a and in this position the nut on bolt 67 can be tightened to firmly clamp the clamping bar 65 in fixed position. Removal of the clamping bar 65 can be effected by loosening the nut and the clamp bolt 67 sufficiently to permit outward withdrawal of the clamping bar 65 to the point where the head of the bolt 68 will slip through the enlarged opening 69 in the saddle 60.

Abrasive is supplied to the impeller i and the tubular control member c through a feed spout f upon which is mounted a feed funnel 72 as shown more particularly in Figs. 1, 2 and 9. The feed funnel 72 has an opening 81 in the bottom thereof in alignment with the open end of the feed spout f. The feed funnel 72 is provided with a secondary supporting bracket 73 which may be cast integrally therewith. The bracket 73 comprises a generally horizontal extending leg portion 74 and a vertically extending leg portion 75. The leg portion 75 is secured to the main bracket 52 by a pair of bolts 76 which extend through horizontally elongated slots 76a provided in the vertical leg

portion 75 and through vertically elongated openings 59b in the flange portion 53 of the main bracket.

The feed spout f comprises generally a tubular conduit portion 71, the upper end of which is provided with laterally extending wing portions 71a shown more particularly in Fig. 10. Each of the wing portions 71a are provided with a bayonet slot 71a through which a securing bolt 78 extends, the securing bolt 78 being threaded into a corresponding threaded aperture in the horizontal leg portion 74 of the bracket 73. Thus, it will be noted that the feed conduit f is rigidly suspended from the horizontal leg portion 74 of the bracket 73 and can readily be removed by unloosening bolts 78. The funnel member 72 may be provided with a reinforcing web 79 which connects the funnel member 72 to the horizontal leg 74 of the bracket 73.

The discharge end of the conduit f may be provided with an outwardly flared flange 82 whose outside diameter approximates the inside diameter of the tubular wall 30 of the control member c. The control member c may be provided with an inwardly extending circular rib 39 which overlaps the outwardly extending flange 82 of the feed conduit f. The flange 82 may be so positioned that it substantially abuts the circular rib 39 when the feed conduit is in proper position for most efficient feeding of the abrasive into the impeller i.

The impeller i may be made as a single casting preferably of some wear-resistant metal and is cast in the form shown in Fig. 6. The impeller generally comprises a circular rim or front wall 85 portion 85 defining a central opening 88 and a circular rear wall portion 86 between which are supported a plurality of spaced radially extending impeller vanes 87. As shown in Fig. 6 the impeller vanes 87 may be cast integrally with the front wall portion 85 and the rear wall portion 86. As shown in Fig. 2 the axial length of the vanes 87 is preferably slightly less than the space between the side edges 35 of the discharge outlet 32 in the control member c. The inner ends of the vanes 87 extend short of the axis of rotation of the rotor to define a center abrasive receiving opening 83 which is generally in line with the discharge outlet of the feed conduit f.

The rear wall portion 86 of the impeller is provided with a collar portion 88a extending rearwardly thereof which collar portion terminates in outwardly extending flange portion 89 which seats against the inside face of the hub member h. The collar portion 88a has an axial length sufficient to properly space the impeller vanes 87 so that the impeller vanes will properly discharge the abrasive in a radial direction through the discharge outlet 32.

The impeller i is fixedly secured to the inner end of the drive shaft 21 by means of a threaded bolt 92 which has a head 92a seated within a depressed recess 93 formed centrally of the rear wall portion 86 of the impeller i. By referring to Fig. 2 it will be noted that when the threaded bolt 92 is in proper position the top face of the head 92a of the bolt is substantially flush with the inside face of the rear wall portion 86.

Preferably it is desirable that impeller vanes 87 equal in number to the abrasive-throwing blades b be provided, as illustrated more particularly in Fig. 3. The advancing face of the impeller vanes 87 should be positioned slightly in advance of the advancing face 10 of the propelling blades b so that the abrasive thrown by the impeller vanes 87

through the discharge outlet 32 in the control member will be deposited gently onto the inner end of the corresponding abrasive propelling blade. In order that the impeller *i* will be properly mounted so as to place the advancing face of the propelling vanes 87 in proper advanced position, the projecting end of the shaft spline 22 is arranged to extend into a corresponding slot provided in the inside face of the collar portion 88a of the impeller *i*, as illustrated in Figs. 2 and 6. The impeller *i* is assembled to the rotor by inserting the same into the tubular control member *c* and inserting the inner end of the shaft spline 22 into the corresponding slot provided in the collar portion 88a of the impeller *i*. The securing bolt 92 is then inserted into a threaded aperture in the end of the drive shaft 21 and tightened so as to hold the impeller flanges 89 in face-clamping engagement with the inside face of the hub member *h*. It will be appreciated that the impeller can be quickly removed by first removing the feed spout *f* by loosening clamping bolt 78 and then removing the impeller bolt 92.

An important feature of this invention is the provision of means for improving the directional control qualities of the bladed rotor and reducing the wear on the impeller *i*, the tubular control member *c* and the rotor *w*. Centrifugal abrasive-throwing mechanisms heretofore constructed comprising a bladed rotor, tubular control member and impeller permit a certain amount of the abrasive to work its way rearwardly of the discharge outlet and between the tubular control member and the impeller. This abrasive is then ground between the stationary and moving parts of the machine destroying both the abrasive and seriously wearing these operative parts and when finally discharged is thrown in all directions.

In the improved construction disclosed in this application this difficulty is largely eliminated and improved directional firing and lessened wear of the operating parts is affected by providing the interior surface of the tubular portion 30 of the control member with an internal helical rib 41 which may be cast integrally with the tubular control member, as shown more particularly in Fig. 7. This helical rib 41 extends from the free edge 36 of the tubular control member 40 inwardly thereof to a plane intersecting the tubular control member at the rear side edge 35 of the discharge opening 32 and which plane is generally parallel to the rotor wall *l*. It will be seen by referring more particularly to Fig. 7 that the rib 41 spirals approximately 3 turns beginning at point 42 at the rear edge 36 of tubular control member and ending at point 43 generally in the plane above-mentioned. Thus a helical passage 44 is provided around the inside face of the tubular portion 30 of the control member *c* which passage is defined by adjacent rib portions 41.

Referring again to the impeller *i* as shown more particularly in Fig. 6, it will be noted that the impeller is provided with a pair of diametrically spaced web portions 93 extending between the rear wall portion 86 of the impeller and the rear flange portion 89 thereof. Assuming that the impeller is rotating in the direction of the arrow shown in Fig. 6, the advancing face 94 of the web portions 93 function as a fan. Any stray abrasive not immediately discharged through the discharge opening 32 of the control member and which works its way rearwardly between the inside face of the tubular control member and the

rear wall portion 86 of the impeller as through the space marked *x* will find itself lodged within the passage 44 between adjacent rib portions 41 of the tubular control member. As the impeller *i* rotates the web portions 93 will create an air current which will drive the abrasive through the passage 44 in the direction of the arrow as shown in Fig. 7 and back out through the space *x* between the rear wall portion 86 of the impeller and the inside face of the tubular control member where it can be again picked up by the impeller vanes 87 and hurled out through the discharge outlet 32 of the tubular control member. The rotating web portions 93 also create an air stream which flows axially outwards towards the feed spout *f* and this moving current of air to a substantial extent prevents the entry of abrasive into the space *x*.

Thus the helical passage 44 and the web portions 93 both cooperate to insure that practically all of the abrasive fed into the impeller *i* is thrown out through discharge outlet 32 of the control member will be deposited on the inner ends of the advancing blades at a predetermined point during rotation thereof.

When the abrasive ejected through the discharge outlet 32 is deposited upon the inner end of the blades at a predetermined point only, the abrasive will be thrown in a predetermined direction, depending upon the clock dial position in which the discharge opening 32 is placed.

It has been found by actual test that the directional control characteristic of the improved centrifugal abrasive impelling machine disclosed in this application is substantially greater than the best directional control results obtained by the best centrifugal abrasive projecting machines heretofore constructed. This is due to the fact that substantially all of the abrasive fed into the impeller *i* is forced outwardly through the discharge opening 32 of the tubular control member. Abrasive fines and other abrasive which normally tends to creep rearwardly of the rotor between the impeller and the tubular control member is largely prevented from such movement by the air stream created by the fan action of the web portions 93. If any such abrasive fines or other abrasive does move rearwardly through the space *x* between the impeller *i* and the tubular control member *c*, it is guided back into the path of rotation of the impeller vanes 87 by the helical passage 44 through which it is driven by the fan action of the web portions 93.

Should any abrasive fines move rearwardly a sufficient distance so as to be unaffected by the air current created by the revolving web portions 93, it will then pass into the circular recess 29 provided in the hub member *h* and readily escape through the vent passages 25 at such low velocity as to have no abrading or damaging effect on surrounding mechanisms. The stray abrasive particles escaping through the vent passages 25 has been found to be substantially confined to dust particles which are not susceptible of being effectively thrown by the abrasive projecting blades *b*. It is believed that the air current created by the rotating web portions 93 causes the abrasive fines to stay within the groove 44 until discharged at the rear point 42 or front point 43 since numerous test runs clearly show that these stray abrasive fines exert no grinding or damaging effect upon either the impeller *i* or the tubular control member *c*, consequently these parts will last indefinitely as far as any grinding action of stray abrasive is concerned. The tubular con-

trol member first wears out at points adjacent the discharge outlet 32 due to the abrading effect of the discharging abrasive contacting the surrounding edges of the opening 32. Stray abrasive fines escaping from the helical passage at point 42 are immediately discharged into the circular recess 29 in the hub from which point it is promptly ejected by bleeder passages 25. No stray abrasive can work its way around the inner end 36 of the control member and into space marked γ since all the stray abrasive which reaches the circular recess 29 escapes thru the vent passages 25.

The tubular control member c may be accurately positioned within the central space 8 of the rotor w by the supporting brackets. It will be appreciated that it is important that the inner end 12 of the blades b be uniformly spaced from the outer surface of the tubular portion 30 of the control member c so as to provide proper operating clearances, and it is further important that the inner end 36 of the control member be inserted the desired distance into the circular recess 29 in the hub member h.

It will be noted that the tubular control member c may be shifted the desired amount to the right or left as shown in Fig. 1 by loosening the bolts 62 and shifting the handle portion 63 of the saddle 60 to the right or left which is permitted by the horizontally elongated slots 62a in the horizontally extending leg portion 61. The tubular control member c may be shifted axially of the rotor so as to properly position the interior end 36 thereof in the circular recess 29 in the hub 30 simply by loosening the bolts 59 and shifting the secondary saddle supporting bracket 57 to the right or left as shown in Fig. 2. The tubular control member c may be vertically raised or lowered by loosening the bolts 59 and shifting the bracket 57 in a vertical direction which is permitted by the vertically elongated slots 53a in the flange portion 53 of the main bracket.

Likewise the feed spout f and associated funnel member 72 may be shifted in six different directions. The flange portion 82 of the feed spout f may be shifted axially of the wheel toward or away from the circular rib 39 of the associated tubular control member by loosening the bolts 76 as shown in Figs. 1, 2 and 10 and shifting the downwardly extending leg portion 75 of the secondary bracket 73 to the right or the left as shown in Fig. 2. The discharge end of the feed spout f may be vertically raised or lowered by unloosening the bolts 76 and shifting vertical leg portion 75 of the secondary bracket 73 vertically which is permitted by the vertically elongated slots 53b provided in the flange portion 53 of the main bracket 52, which feature is more particularly shown in Fig. 13.

The discharge end of the feed spout f may be shifted laterally to the right or left as shown in Fig. 1 by unloosening the bolts 78 and then shifting the feed spout f laterally to the right or left as shown in Fig. 1 which is permitted by the elongated slots 77b provided in wing portions 77 extending laterally from the upper end of the feed spout f.

Thus it will be appreciated that the tubular control member c as well as the feed spout f and its associated funnel member 72 are both susceptible of a six-way adjustment so that these parts can be accurately centered and positioned for most efficient operation. The adjustment is affected by merely loosening paired clamp bolts, shifting the parts in the desired direction and the

desired amount and then tightening the clamp bolts so as to accurately hold these parts in the desired fixed position to which they have been adjusted. Thus the tubular control member c may be adjusted upward or downward, to the right or left and axially in both directions so that the proper accurate clearance is provided between the interior ends 12 of the blades b and the outer surface of the tubular control member and further to position the interior end 36 of the tubular control member in proper position within the circular abrasive-receiving recess 29 in the hub member h. Likewise the discharge end of the feed spout f may be vertically adjusted, laterally adjusted to the right or left, and axially adjusted in both directions so as to properly center the outwardly extending flange portion 82 on the inner discharge end of the feed spout in proper position within the tubular control member c and in proper abutting relation to the circular rim 39 of the tubular control member.

It will be noted by referring to Fig. 1, that the bracket structure supporting the tubular control member c and the feed spout f are positioned off to one side from the axis of rotation of the rotor so as to give clear, unobstructed view of the control cage. The proper clearance between the outer surface of the control cage and inner ends of the blades b and the inner edges 1 of the side wall plates 1 and 2 of the wheel can thus be visibly determined and provided for. Clear unobstructed view is also provided for centering the flange 82 of the feed pipe in proper position within the tubular control member c and in proper abutting relation to the rib 39. The inner end 36 of the tubular control member may be inserted into the circular recess 29 in the hub h the proper axial distance by providing a mark on the outer surface of the tubular control member so positioned as to align with the outside face of the side wall plate 2 when proper axial insertion of the tubular control member c has been effected. Proper and accurate positioning of the tubular control member c and the feed pipe f with reference to the rotor w is thus assured.

Extensive tests of the centrifugal abrasive machine disclosed in this application have shown that a higher degree of directional control of the thrown abrasive is attained than has ever been attainable by the best centrifugal abrasive projecting machine heretofore produced. This results from the fact that substantially no stray abrasive can pass on to the abrasive propelling blades b. Stray abrasive and abrasive fines which may conceivably work its way rearwardly between the control member c and the impeller i to the space x is driven forwardly into the path of the impeller vanes 87 which throws this stray abrasive out through the discharge outlet 32 in the control member c under directional control. Extensive tests have further revealed that this tubular control cage is subjected to substantially no wear except only the wear around the inside surface of the tubular control member between the rib 39 and the inner end 43 of the helical rib 41, which area is swept by abrasive, and the wear along the side edges 33, 34 and 35 of the discharge outlet 32 incident to the discharge of abrasive outwardly through the discharge outlet 32, and wear in the mechanism described in this application has been found by actual test to be less than the wear in tubular control members heretofore constructed. Wear on the impeller i is also substantially confined to the advancing faces of the abrasive projecting vanes 86 thereof. The web 7

portions **93** serve to create a current of air which keeps stray abrasive away from the collar portion **88a** and the flange portion **88** of the impeller, so that these parts are subjected to substantially no wear.

It has been further found from tests made of the machine herein disclosed that the blades **b** wear with greater uniformity so that the blades and the rotor remain in dynamic balance until 10 the face portion **10** of the blades are substantially entirely worn away.

Any stray abrasive fines which reach the circular recess **29** in the hub **h** is promptly discharged to the vent passages **25**, and no abrasive 15 works its way around the inner end **36** of the tubular control member and into the clearance space **y** between the outside surface of the tubular control member and the inner peripheral edge **1** of the side wall plate **1**. Thus the side wall plate 20 **1** of the rotor is subjected to little or no wear during operation.

It will be appreciated that when a bladed abrasive throwing wheel is rotated at blasting velocity, air disturbances necessarily result, causing air 25 current movements within the central opening of the wheel, which, by reason of the high speed rotation of the blades, is a region of low pressure. Air flows into this central region through the feed spout or space surrounding the feed spout 30 and the tubular control member which is all positioned on one side of the wheel, the rear side of the wheel in prior centrifugal wheels being closed at the back. By the provision of vents or bleeder passages **25** through which air can circulate freely either to enter the wheel or flow from the wheel to stabilize and balance the pressure within the central region of the wheel, greatly improved results in directional control efficiency and reduced wear are obtained, since the 35 40 turbing air currents set up by the rotation of the bladed wheel are thus substantially obviated or the effect thereof greatly lessened.

With my improved centrifugal blasting machine as herein disclosed, actual tests have shown 45 that little or no stray abrasive or abrasive fines are discharged from the vent openings, which is a further indication of the high directional control efficiency obtained. This highly desirable result appears to be attributable to the fact that the impeller webs **93** in cooperation with the helical passages **44** in the tubular control member prevent the rearward movement of stray abrasive or return such stray abrasive to the interior of the tubular control member, and to the fact that air 50 55 is swept into the central region through the vents provided in the hub, which movement of air would act to prevent the rearward movement of the stray abrasive so that the abrasive is retained in such position within the tubular control member that it can readily be propelled out through the discharge outlet therein by the impeller. While the highly desirable results produced by my improved abrasive throwing machine have been conclusively proven by numerous tests, 60 65 the theory of its operation and the movement of abrasive and air currents can only be conjectured, since it is almost impossible to measure same under high speed operating conditions.

It has been found further, and demonstrated 70 to be a fact, that in my improved abrasive throwing machine the exterior of the tubular control member evidences little sign of wear in operation, and that in my improved device the tubular control member is subjected to less abrasive wear than the tubular control members in prior art

devices. Any back-sweep or circular movement of abrasive-laden air around the exterior of the tubular control member appears to be eliminated, as evidenced by the fact that there is little sign of wear on the exterior surface of the tubular control member, and the abrasive moves with uniformity and free from undesirable air current disturbances and is directed from the discharge outlet of the tubular control member immediately and directly onto the inner end of the blades as 10 they pass the discharge outlet.

The centrifugal abrasive propelling machine herein disclosed is made of relatively few parts, so constructed as to insure proper and speedy assembly thereof for most efficient operation. The 15 tubular control member **c**, the impeller **i**, and the hub member **h** can each be made as a one-piece casting. The side wall plates **1** and **2** and the spacing studs **3** can be made of steel and the blades **b** can be made of a suitable wear-resisting 20 metal, sufficiently tough to resist the shocks and metal fatigue incident to operation.

While certain novel features of the invention have been disclosed and are pointed out in the annexed claims, it will be understood that various omissions, substitutions and changes may be 25 made by those skilled in the art without departing from the spirit of the invention.

What is claimed is:

1. In an abrading machine, a rotor having a 30 plurality of blades terminating short of the axis of rotation of said rotor to define an abrasive admitting space, a tubular abrasive feeding device extending into said abrasive admitting space, said feeding device having an abrasive discharge 35 outlet in the tubular sidewall thereof operative to direct abrasive into the path of rotation of said blades, means for supplying abrasive to said feeding device positioned forwardly of said discharge outlet, an impeller rotatably mounted within said tubular feeding device operative to project the abrasive through the discharge outlet 40 therein, a passage associated with said feeding device extending rearwardly of said discharge outlet, and a driving element associated with said 45 impeller for returning stray abrasive positioned rearwardly of the adjacent rear side edge of said outlet along said passage to a position where it may be discharged through said discharge outlet.

2. In an abrading machine, a rotor having 50 spaced radially extending abrasive propelling blades mounted for rotation at high speed, a tubular control member normally held in stationary position within said rotor, said control member having an abrasive discharge outlet in the sidewall 55 thereof, a conduit for supplying abrasive to said control member positioned forwardly of the discharge outlet therein, a rotatably mounted impeller positioned within said tubular control member having impeller vanes operative to eject 60 abrasive through said discharge outlet into the path of rotation of said blades, and means including a guide passage and an abrasive driving element associated with said tubular control member and said impeller positioned rearwardly 65 of said discharge outlet for moving stray abrasive into a position where it will be thrown by said impeller vanes through said discharge outlet.

3. In an abrading apparatus, a rotor adapted 70 to be driven at high rotative speed having a plurality of spaced substantially radial extending blades mounted thereon, said blades extending inwardly short of the axis of rotation of said rotor to define a central abrasive admitting space, a tubular control member having an abrasive 75

- discharge outlet in the tubular side-wall thereof axially spaced from the rear edge of said tubular control member, an impeller positioned within said tubular control member and fixed to rotate with said rotor, said impeller having a plurality of abrasive propelling vanes axially positioned between the side edges of said blades operative to throw abrasive through said discharge outlet into the path of rotation of said blades, means for supplying abrasive to said impeller, and a helical passage associated with the inner surface of said tubular control member for returning stray abrasive into a position where the same will be swept out of the discharge outlet of said tubular control member by said impeller vanes.
4. In an abrading machine, a rotor having a plurality of blades terminating short of the axis of said rotor to define an abrasive admitting space, a tubular abrasive feeding device extending into said abrasive admitting space, said feeding device having an abrasive discharge outlet in the tubular side wall thereof operative to direct the abrasive into the path of rotation of said blades, means for supplying abrasive to said feeding device, and a helical passage extending along the inner surface of said tubular feeding device from the rear edge thereof to the vicinity of said discharge outlet, said passage being operative to guide stray abrasive located rearwardly of the adjacent rear side edge of said outlet to a position where it may be discharged through said discharge outlet.
5. In an abrading machine, a rotor having a plurality of blades terminating short of the axis of said rotor to define an abrasive admitting space, a tubular abrasive feeding device extending into said abrasive admitting space, said feeding device having an abrasive discharge outlet in the tubular sidewall thereof operative to direct the abrasive into the path of rotation of said blades, means for supplying abrasive to said feeding device, and a helical rib fixed to the inner surface of said tubular feeding device and extending from the vicinity of the rear edge of said feeding device to the vicinity of said discharge outlet, said rib defining a helical passage operative to guide stray abrasive forwardly to a position where it may be discharged through said discharge outlet.
6. In an abrading machine, a rotor having a plurality of blades terminating short of the axis of rotation of said rotor to define an abrasive admitting space, a normally stationary tubular abrasive feeding device extending into said abrasive admitting space, said feeding device having an abrasive discharge outlet in the tubular side wall thereof, an impeller having a plurality of abrasive propelling vanes mounted for rotation and operative to throw abrasive through said discharge outlet and into the path of rotation of said blades, said impeller having a fan element associated therewith positioned rearwardly of said propelling vanes operative to create a current of air which resists movement of stray abrasive in said tubular feeding device rearwardly of the rear side edge of the discharge outlet therein.
7. In an abrading machine, a rotor having a plurality of blades terminating short of the axis of rotation of said rotor to define an abrasive admitting space, a normally stationary tubular abrasive feeding device extending into said abrasive admitting space, said feeding device having an abrasive discharge outlet in the tubular side wall thereof, an impeller having a plurality of abrasive propelling vanes mounted for rotation and operative to throw abrasive through said discharge outlet and into the path of rotation of said blades, said impeller having a plurality of fan elements positioned rearwardly of said propelling vanes, said fan elements being operative upon rotation thereof to create a current of air which resists movement of stray abrasive in said tubular feeding device rearwardly of the rear side edge of the discharge outlet therein.
8. In an abrading machine, a rotor having a plurality of blades terminating short of the axis of rotation of said rotor to define an abrasive admitting space, a normally stationary tubular abrasive feeding device extending into said abrasive admitting space, said feeding device having an abrasive discharge outlet in the tubular side wall thereof, an impeller having a plurality of abrasive propelling vanes mounted for rotation and operative to throw abrasive through said discharge outlet and into the path of rotation of said blades, means associated with the inner surface of said tubular feeding device for guiding stray abrasive located rearwardly of the adjacent rear side edge of said discharge outlet in a direction forwardly towards said discharge outlet, and means associated with said impeller operative to drive said stray abrasive forwardly towards the discharge outlet in said feeding device.
9. In an abrading machine, a rotor having a plurality of blades terminating short of the axis of rotation of said rotor to define an abrasive admitting space, a normally stationary tubular abrasive feeding device extending into said abrasive admitting space, said feeding device having an abrasive discharge outlet in the tubular side wall thereof, a conduit for supplying abrasive to said feeding device positioned forwardly of said discharge outlet, an impeller having a plurality of abrasive propelling vanes mounted for rotation and operative to throw abrasive through said discharge outlet and into the path of rotation of said blades, and cooperating abrasive guiding and abrasive driving means associated with said tubular feeding device and said impeller positioned rearwardly of said discharge outlet and said vanes operative to move stray abrasive forwardly towards the discharge outlet in said feeding device.
10. In an abrading machine, a rotor having a plurality of blades terminating short of the axis of rotation of said rotor to define an abrasive admitting space, a normally stationary tubular abrasive feeding device extending into said abrasive admitting space, said feeding device having an abrasive discharge outlet in the tubular side wall thereof axially spaced between the side edges of said blades, an impeller having a plurality of abrasive propelling vanes fixed to rotate with said rotor and operative to throw abrasive through said discharge outlet and into the path of rotation of said blades, and cooperating means associated with said tubular feeding device and said impeller operative to drive stray abrasive forwardly towards the discharge outlet in said feeding device, said cooperative means including a helical passage extending along the inner surface of said feeding device from the vicinity of the rear edge thereof to the vicinity of said discharge outlet, and a fan element associated with said impeller positioned rearwardly of said propeller vanes in cooperative relationship to said helical passage.
11. In an abrading machine, a hub member having a central opening, a drive shaft having one end thereof extending into said opening, a

- rotor disk mounted on said hub and having a central opening, abrasive propelling blades supported by said rotor disc and terminating short of the axis of rotation of said disc to define a central abrasive admitting space, a tubular control member extending into said central space having the rear edge thereof extending into a circular recess provided in said hub member, said tubular control member having an abrasive discharge outlet in the side wall thereof of limited peripheral length and positioned between the side edges of said blades, an impeller fixed to said hub member operative to forceably eject the abrasive through the discharge opening in said tubular control member and means for supplying abrasive to said impeller, said hub member having passages therein leading from said circular recess to the exterior of said hub.
12. In an abrading machine, a rotatably mounted drive shaft, a hub member mounted on said shaft, a rotor including a disk mounted on said hub member and having a central opening, abrasive propelling blades mounted on said disk and extending inwardly to a point substantially 25 in axial alignment with the peripheral edge of the central opening in said disk, the inner ends of said blades defining a central abrasive-receiving space, a tubular control member extending into said central abrasive-receiving space, an abrasive discharge outlet in the tubular sidewall of said control member, an impeller for forceably ejecting abrasive supplied thereto through the discharge outlet of said control member and into the path of rotation of said blades, said impeller 30 including a disk-shaped rear wall portion, a plurality of abrasive propelling vanes mounted on said portion, a collar portion having a diameter substantially equal in diameter to said disk-shaped rear wall portion and formed on said rear wall portion, said collar portion seating against the inside face of said hub member, a key element engaging said hub member, drive shaft and said collar portion for retaining the same in fixed position, and means for securing said 35 impeller to the end of said drive shaft.
13. In an abrading machine, a rotor having a plurality of blades terminating short of the axis of rotation of said rotor to define an abrasive-admitting space, a tubular abrasive feeding device extending into said abrasive-admitting space, said feeding device having an abrasive discharge outlet in the tubular side wall thereof, a feed spout for supplying abrasive to said feeding device, and means for supporting said feed 40 spout and said feeding device in operative position, said supporting means including a main bracket positioned entirely to one side of said feed spout and tubular feeding device, a saddle member adjustably connected to and extending laterally from said main bracket for supporting said feeding device, and means adjustably connected to and extending laterally from said main bracket and above said tubular feeding device for supporting said feed spout.
14. In an abrading machine, a rotor having a plurality of blades terminating short of the axis of rotation of said rotor to define an abrasive-admitting space, a tubular abrasive feeding device extending into said abrasive-admitting space, said feeding device having an abrasive discharge outlet in the tubular side wall thereof, and means for supporting said feeding device in operative position, said supporting means including a main bracket fixedly positioned entirely to one side of said feeding device, a saddle member extending laterally from and adjustably connected to said main bracket, said saddle member having an arcuate surface upon which a tubular face of said abrasive feeding device is positioned, and a clamping bar adjustably secured to said saddle member extending partially into said abrasive feeding device for removably securing said feeding device to said saddle member.
15. In an abrading machine, a rotor having a plurality of blades terminating short of the axis of rotation of said rotor to define a central space, a tubular abrasive feeding device extending into said central space, said feeding device having an abrasive discharge outlet in the tubular side wall thereof operative to direct the abrasive into the path of rotation of said blades, an abrasive feed spout for supplying abrasive to said rotor, a feed funnel positioned over the abrasive receiving end of said feed spout, and means for supporting said feed spout and feed funnel in operative position, 10 said supporting means including a main bracket fixedly positioned entirely to one side of said feed spout, a secondary bracket connected to said feed funnel and adjustably secured to and extending laterally from said main bracket, winged 15 portions extending laterally from the upper end of said feed spout, means for removably connecting said winged portions to said secondary bracket and a saddle member connected to and extending laterally from said main bracket for 20 supporting said feeding device.
16. In a centrifugal abrading machine, a rotatably mounted shaft, a rotor head fixed to said shaft, abrasive throwing blades supported by said rotor head extending inwardly short of the axis 25 of rotation of said head to define a central space, a tubular control member extending into said central space having an abrasive discharge outlet in the tubular side wall thereof, abrasive supply means for conducting abrasive into said tubular 30 control member, a rotatably mounted impeller positioned within said tubular control member operative to eject abrasive through said discharge outlet and into the path of rotation of said blades, an abrasive discharge passage extending through 35 said rotor head axially and rearwardly from a point adjacent the inner end of said tubular control member, and means associated with said tubular control member defining an abrasive passage extending from adjacent the inner end of 40 said tubular control member to the discharge outlet therein for guiding stray abrasive.
17. In a centrifugal abrading machine, a rotatably mounted shaft, a rotor head comprising a hub member fixed to said shaft and a side wall 45 disc fixed to said hub member, abrasive throwing blades supported by said disc member extending inwardly short of the axis of rotation of said head to define a central space, a tubular control member extending into said central space having 50 an abrasive discharge opening in the side wall thereof, abrasive supply means for conducting abrasive into said tubular control member, impeller means positioned within said tubular control member for ejecting abrasive through the 55 discharge opening in said tubular control member into the path of rotation of said blades, said hub member having a cavity therein into which the inner end of said tubular control member extends, said hub member having a vent passage 60 extending from said cavity outwardly to the exterior thereof.
18. In a centrifugal abrading machine, a rotatably mounted shaft, a rotor head mounted on said shaft, abrasive throwing blades sup- 75

- ported by said rotor head extending inwardly short of the axis of rotation of said head to define a central space, a tubular control member extending into said central space having an abrasive discharge opening in the side wall thereof, abrasive supply means for conducting abrasive into said tubular control member, impeller means positioned within said tubular control member for ejecting abrasive through the discharge opening in said tubular control member into the path of rotation of said blades, said rotor head having a groove extending continuously around the inner end of said tubular control member, pockets in said rotor head opening into said groove, and a vent passage extending from each of said pockets to the exterior of the rotor head.

19. In a centrifugal abrading machine, a rotatably mounted shaft, a rotor head comprising a hub member fixed to said shaft and a side wall disc fixed to said hub member, abrasive throwing blades supported by said disc extending inwardly short of the axis of rotation of said head to define a central space, a tubular control member extending into said central space having an abrasive discharge opening in the side wall thereof, an abrasive supply means for conducting abrasive into said tubular control member, impeller means positioned within said tubular control member for ejecting abrasive through the discharge opening in said tubular control member into the path of rotation of said blades, said hub member having a groove extending continuously around the inner end of said tubular control member, pockets in said hub member extending outwardly from said groove, and a vent passage extending from each of said pockets in a generally axial direction outwardly to the exterior of said hub member.

20. In an abrading machine, a drive shaft mounted for high speed rotation, a rotor head fixed to said drive shaft, a plurality of blades mounted on said head and terminating short of the axis of rotation of said rotor head to define an abrasive admitting space, a normally sta-

tionary tubular abrasive feeding device extending into said space, said feeding device having an abrasive discharge outlet in the tubular side wall thereof, abrasive supply means for conducting abrasive into said tubular abrasive-feeding device positioned forwardly of the discharge outlet therein and an impeller mounted on said shaft and having a plurality of abrasive propelling vanes extending into said feeding device and operative to throw abrasive through said discharge outlet and into the path of rotation of said blades, said rotor head having a rotatable portion rearwardly of said abrasive discharge outlet in said abrasive-feeding device, said rotatable portion having air inlet ports extending therethrough to admit air into said tubular abrasive feeding device, whereby to balance any differences in pressure in said abrasive admitting space resulting from the high speed rotative movement of said bladed rotor head.

21. In a centrifugal abrading machine, a rotatably mounted shaft, a rotor head mounted to rotate with said shaft, abrasive throwing blades supported by said rotor head extending inwardly short of the axis of rotation of said head to define a central space, a tubular control member extending into said central space and having an abrasive discharge opening in the side wall thereof, abrasive supply means for conducting abrasive into said tubular control member, impeller means positioned within said tubular control member for ejecting abrasive through the discharge opening in said tubular control member into the path of rotation of said blades, said rotor having a rotatable portion rearwardly of the abrasive discharge opening in said control member, said rotatable portion having a cavity therein into which the inner end of said tubular control member extends, the rotatable portion of said rotor head having a plurality of vent passages therein leading from the exterior of the rotor head to the cavity to admit air to the interior of the tubular control member.

CHESTER E. UNGER.
